UNITED STATES PATENT OFFICE.

MILES F. MOORE, OF LOS ANGELES, CALIFORNIA, ASSIGNOR OF ONE-HALF TO SYDNEY I. WAILES, OF LOS ANGELES, CALIFORNIA.

RAILWAY-CROSSING.

1,273,085.

Specification of Letters Patent. Patented July 16, 1918.

Application filed June 20, 1916. Serial No. 104,679.

To all whom it may concern:

Be it known that I, MILES F. MOORE, a citizen of the United States, residing at Los Angeles, in the county of Los Angeles and 5 State of California, have invented new and useful Improvements in Railway-Crossings, of which the following is a specification.

This invention relates to railway crossings, and more particularly to railway crossings, 10 ings the intersecting rails of which are adapted for co-action with flanged rolling-stock wheels and in which a substantially uninterrupted rail surface is provided for traverse by such flanged wheels at the intersecting section. In railway crossings as ordinarily 15 constructed, the rails are interrupted to provide flange-ways to permit the transverse passage of rolling-stock over a set of rails, and the impact incident to the rolling-stock-wheel treads in falling into such flange-ways causes the rapid destruction of the crossing 20 as well as shortening the life of rolling-stock features such as motor frames, wheels, etc., all as will be understood by those 25 familiar with this art. It is also highly desirable that the noise occasioned by the traverse of rolling-stock wheels over standard crossings be eliminated.

In accordance with the present invention 30 movably mounted means for filling the flange space of the rails being traversed by rolling-stock wheels at any given time are provided, together with means for moving such first named means into position to provide an approximately uninterrupted rail surface capable of withstanding the severe 35 strains incident to service so that the rolling stock wheels and the loads carried thereby may be moved across intersecting tracks or 40 rails with a minimum of wear and tear on trackage and rolling-stock and the objectionable noise aforementioned. The invention further provides means whereby the 45 means for closing the flange-ways of rails to be traversed by rolling-stock moving in a given direction may be moved into position simultaneously with the moving out of position of such flange-way closing means as are provided in tracks or rails intersecting the 50 rails in use and which flange-way closing means would otherwise obstruct the flanges of said rolling-stock wheels. The invention further is concerned with the provision of heating means in association with devices of 55 this general nature to prevent binding or

seizure of the movable members thereof due to ice, snow, and the like. The means for moving the first named means into position may operate automatically, that is, may be actuated by the wheels of the rolling-stock 60 upon approach to the crossing, or the same by suitable modification, may be actuated voluntarily as from a switch tower or the like.

The invention has for a further object the 65 provision of a railway crossing of the general nature stated which may be self-contained, which will be relatively simple and inexpensive in construction and organization when its other features of superiority 70 such as durability, freedom from liability to get out of order or repair, noiselessness of operation, and general superiority in serviceability are considered.

With the above and other objects in view, 75 the invention consists in the novel and useful provision, formation, combination, association and relative arrangement of parts, members and features, all as will be herein-after described, shown in the drawings, and 80 finally pointed out in claims.

In the drawings:

Figure 1 is a fragmentary plan view of a railway crossing constructed and organized in accordance with the invention, parts being broken away and sectioned for clearness of illustration;

Fig. 2 is a vertical sectional view taken on the line α^2 , Fig. 1;

Fig. 3 is an enlarged fragmentary detail 90 view of a portion of the showing in Fig. 2, the parts however being shown in a different position than in Fig. 2;

Fig. 4 is a sectional view, partly in elevation, taken on the line $\alpha^4-\alpha^4$, Fig. 3, and 95 looking in the direction of the appended arrows;

Fig. 5 is an enlarged detail plan view of certain features of the invention;

Fig. 6 is a view similar to Fig. 2 of a 100 modified form of the invention; and

Fig. 7 is a plan view, partly broken away and sectioned for clearness of illustration, of a still further modified form of the invention, this figure showing heating means in 105 combination with or associated with other features of the invention.

Corresponding parts in all the figures are designated by the same reference characters.

Referring with particularity to the draw- 110

ings, in the embodiment of the invention therein shown, A designates, in each instance, a rail of a pair of rails adapted to be traversed in a given direction by rolling-
5 stock wheels, B designates, in each instance, a rail of another pair of rails shown as at right angles to the rails A and intersecting the same, C designates, in each instance, means for closing a flange-way provided in
10 the rails A to permit rolling-stock-wheel flanges traversing the rails B to cross the rails A, D designates, in each instance, means for closing a flangeway provided in the rails B to permit the crossing of such rails B by
15 rolling-stock traversing the rails A, e designates in each instance, actuating means for a means C, d designates, in each instance, means for actuating a means D, E in each instance, designates means for operative connection between a means C and a means D,
20 and F designates means of connection to cause the simultaneous operation of all of the means C and D provided at the intersection of a given pair of rails A and B.
25 The rails A each comprise a rail surface or portion 8 adapted to co-act with the treads of rolling-stock wheels, a guard portion 9, and a web 10 adapted to lie upon a roadbed or be otherwise suitably sup-
30 ported, there being a flange-way 11 between the rail surface 8 and the guard portion 9 and extending along each rail A and terminating at any preferred point. Each rail B is similarly organized and comprises a
35 rail surface portion 12, a guard portion 13, and a web 14 adapted to lie upon the roadbed or be otherwise suitably supported, a flange-way 15 being provided between the rail surface 12 and the guard portion 13 and extending along the rails B and terminating at any preferred point.
40 In the form of construction shown in the drawings the rail structure is shown as of box-like cross section, though the same may be of any other preferred and
45 suitable cross section.

The means C for filling or closing the flange-ways 15 provided through the rails 8 may each consist of a reciprocatory member 16 adapted to be vertically reciprocated and guided in a chamber 17. The member 16 is preferably in the form of a rectangular block and is adapted to bridge the flange-way 15 in which it is installed at the respective rail A and in line with such rail A. The member 16 is provided with a plurality of shoulders 18 at its lower portion and is provided with a pivot 19 below each such shoulder 18, a plurality of links 20 being provided to support the body or member 16 in elevated flange-way-bridging position and to assist in the withdrawal of the same from such elevated position. Each link 20 is bifurcated as at 20^a and secured to the body 16 by means of a pivot 19, an

orifice 20^b, preferably slightly elliptical in 65 form accommodating the respective pivot 19.

Each of the actuating means e preferably comprises a member 21 chambered in the body of the rail B, a slide 22 adapted to ride on the web 14 of the rail B, a link 23 pivotally connected at one end to the slide as at 24 and pivotally connected at its other end to the member 21 as at 25, and the links 20 which are loosely pivotally connected with the slide 22 as at 26. Elongated apertures 26^a are provided in the link ends adjacent to the slide to receive horizontal pivots 27 carried by the slide, and the slide 22 is recessed as at 28 to form a seat for the lower ends of the links 20 when the member 80 or body 16 is in elevated position. The slide 22 extends from a point beneath the member 21, under the member 16 and the links 20 to a point inside of the rails A where it is provided with a vertical pivot 22^a and the member 21 is pivotally connected to the respective rail B as at 29 and normally extends into the path of a rolling-stock wheel flange to be depressed thereby to draw the slide, through the link 23, in such direction 90 as through the links 20 to retract or lower the member or body 16 and thus clear the flange-way to be used.

Each means D preferably consists of a member or body 30 chambered in the re- 95 spective rail A at the intersection of such rail with a rail B, as at 31, such body 30 being constructed and organized similarly to the body 16 constituting the means C.

Each actuating means d is constructed 100 similarly to the actuating means e, and comprises a member 35 chambered in a rail A as at 36, a slide 37 adapted to ride on the web 14 and inside of the rail structure, a link 38 pivotally connected at one end to the slide as at 39 and pivotally connected at its other end to the member 35 as at 40. The member 35 is disposed in a flange-way 11 and in position to be engaged and depressed by the flange of a rolling-stock 110 wheel. The slide 37 extends from beneath the member 35, beneath and past the body or member 30, said members being cut away and slidably interfitted in the ordinary manner, and past the links 34 and to a 115 point between the rails B where it is provided with an upright pin 43.

At each point of junction of a rail A and a rail B and within the inclosure formed by such rails, is a bell crank 44 constituting the means E. Such bell crank 44 is pivoted as at 45 to an extension 46 of the web 14 and one arm 47 of the bell crank 44 is bifurcated as at 47^a to embrace the pivot 43 of the respective slide 37 and the other arm 48 of the bell crank 44 is bifurcated as at 48^a to receive and engage the pivot 22^a of the respective slide 22. The walls

of the box-like rail structure are cut away to permit intrusion and movement of the bell crank arms 47 and 48.

The connecting means F preferably comprises a plurality of horizontal links 49, each connected at one end to an arm 50 of a bell crank 44 and to an arm 47 of another bell crank 44 as will be clearly understood by reference to Fig. 1 of the drawings.

10 By this means actuation of one of the flange-way closing means will cause the simultaneous actuation of all of the others of any particular group of such flange-way closing means so that contact of rolling-stock flanges 15 with the respective actuating means c or d will so set the means C and D, with relation to each other and to the rails that the treads of the rolling-stock wheels will have an approximately uninterrupted rail surface to 20 traverse and the means C or D lying in the plane of the advancing rolling-stock-wheel flanges will be in depressed position.

In the modified form of construction shown in Fig. 6, the means and elements 25 hereinbefore described may be employed, or part of the actuating means may be eliminated, in accordance with preference, as in this form of construction one of the slides 22 or 37 may be provided with a series of 30 rack teeth 51 with which meshes a pinion 52 mounted on a short shaft 53 beneath the web 10 or 14, such web being cut away to permit intrusion of the pinion. The shaft 53 is journaled in suitable bearings and has secured 35 thereto diametrically opposed arms 54 and 55 which are connected by means of links 56 and 57, respectively, with an operating handle or lever 58 which is suitably pivotally mounted as at 59. Such operating handle may be 40 disposed, with slight modification of the linkage, in a switchman's tower or at any other preferred point of control.

In the modified form of construction shown in Fig. 7, the bell cranks 44 and 45 links 49 are shown as inclosed in a casing or closed trough 60 and heating means G are disposed in such trough to prevent the binding of parts by ice, sleet or the like, the entire crossing being maintained at a 50 temperature sufficiently high to prevent such freezing up or seizing of parts. The heating means G preferably comprises a series of coils 61 of resistance wire disposed in the trough 60 and being connected at one 55 end to a rail A and connected at the other end with any suitable supply of electrical energy.

This is shown in the main diagrammatically in the drawing and will be clearly 60 understood by anyone versed in such matters.

Buffers 62 and 63 may be provided if desired, to yieldingly limit the travel of the slides 22 and 37, the buffer 62 by allowing 65 slight over-travel of the slides compensat-

ing for unusual flange depth of rolling-stock wheels, allowing the members 21 and 35 to be depressed slightly farther than necessary to raise the means C and D the required height. Such buffers may be used 70 in connection with any of the forms of the invention illustrated.

The operation, method of use and advantages of the invention will be readily understood from the foregoing description, taken 75 in connection with the accompanying drawings and the following statement:

The members 21 of the actuating means c being disposed in the flange-ways of the rails B and outwardly of the point of intersection of the rails A and B, that is to say, in the path of rolling-stock advancing toward the intersection, such members will be engaged and depressed by the flanges of the rolling-stock wheels and the slides 22 of 80 such members as are first depressed will be retracted by means of the links 23, drawing the respective links 20 outwardly and thus lowering the respective bodies or members 16 to clear such flange-ways of obstructing bodies or members 16. Simultaneously with the depressing of the members 21, and the retraction of the bodies 16, the bodies 30 will be elevated, due to the cross-connections through the bell cranks 44 85 of the means E and the connecting means F. It will thus be seen that rolling-stock approaching the intersection in either direction on the rails B will by flange contact depress the members 21 first encountered, 100 thereby positioning all of the members and parts to provide approximately uninterrupted rail surface for rolling stock traverse and clearing the flange-ways to be used. Similar actuation, with reversal of 105 movement, however, occurs when other rolling-stock approaches the intersection on the rails A, striking members 35, and depressing the members or bodies 30 while the members or bodies 16 are raised to provide approximately uninterrupted rail surface of the rails A. In the form of construction shown in Fig. 7, by manipulation of the lever 58, the slide to which motion is given through the pinion 52 will be moved correspondingly, and through the bell cranks 44 and connecting rods 49 cause the actuation of all of the means C and D connected therewith and thus provide uninterrupted 110 rail surface of the rails A or B as the case 115 may be.

It will be understood that when the means C and D are to be operated by means of the lever 58, or equivalent means, the contact members 21 and 35 with their respective 120 links 23 and 38 may be dispensed with if desired, though their presence will in no wise interfere with the voluntary actuation of the means C and D, but will in addition 125 to the voluntary means of actuation, provide 130

means for automatically actuating the members C and D upon the approach of rolling-stock, just as though the lever 50 and train of operative connections to the pinion were not present.

It is manifest that many variations may be made in departing from the specific disclosure herein in adapting the invention to varying conditions of use and service, without departing from the spirit of the invention and the terms of the following claims.

Having thus disclosed my invention, I claim and desire to secure by Letters Patent:

1. The combination, with intersecting rails for flanged rolling-stock wheels; of movably mounted means for producing an approximately uninterrupted traction surface of one rail at the point of intersection of the rails, and means positioned to be actuated by a rolling-stock wheel for moving said first named means; said last named means comprising a member normally projecting into the path of travel of the rolling-stock wheel, and another member chambered in the trackage and reciprocated by and movable responsive to movement of said first named member; and said first named means comprising a body mounted for elevation and depression in the traction-wheel-flange-accommodating-rail-channel and operatively connected with said second named member; a link to that end being provided between said second named member and said body, pins respectively upon said second named member and said body whereby said link loosely pivotally connects the latter, and shoulders upon said second named member and said body engaging with said link to transmit the strain of the load imposed upon said body to said second named member when said body is in elevated position.
2. The combination, with intersecting rails for flanged rolling-stock wheels; of movably mounted means for producing an approximately uninterrupted traction surface of one rail at the point of intersection of the rails, and means positioned to be actuated by a rolling-stock wheel for moving said first named means; said last named means comprising a member normally projecting into the path of travel of the rolling-stock wheel, and another member chambered in the trackage and reciprocated by and movable responsive to movement of said first named member; and said first named means comprising a body mounted for elevation and depression in the traction-wheel-flange-accommodating-rail-channel and operatively connected with said second named member; a link being provided to that end which constitutes a direct support for said body when the body is in elevated position and which link transmits the weight of the load to said second named member.
3. The combination, with intersecting rails

for flanged rolling-stock wheels; of movably mounted means for producing an approximately uninterrupted traction surface of one rail at the point of intersection of the rails, and means positioned to be actuated by a rolling-stock wheel for moving said first named means; said last named means comprising a member normally projecting into the path of travel of the rolling-stock wheel, and another member chambered in the trackage and reciprocated by and movable responsive to movement of said first named member; and said first named means comprising a body mounted for elevation and depression in the traction-wheel flange accommodat⁷⁵ing rail channel and operatively connected with said second named member; a buffer yieldingly limiting the play of said second named member.

4. The combination, with two pairs of intersecting rails for flanged rolling-stock wheels; of means for producing approximately uninterrupted rail traction surface at the points of intersection of said rails, members for operating said last named means and chambered in the trackage, there being a plurality of such members for each point of rail intersection, devices operatively connecting such members at each rail intersection, and means operatively connecting said devices whereby all such members at all rail intersections are operatively inter-related.

5. In a railway crossing, members movably chambered in the trackage at rail intersections, bell cranks connecting such members at each intersection, and link rods connecting such bell cranks.

6. In a railway crossing, members movably chambered in the trackage at rail intersections, bell cranks connecting such members at each intersection, and link rods connecting such bell cranks; further members being operatively connected with said first named members and positioned to be depressed by engagement with rolling-stock wheels.

7. In a railway crossing, members movably chambered in the trackage at rail intersections, bell cranks connecting such members at each intersection, and link rods connecting such bell cranks; further members being operatively connected with said first named members and positioned to be depressed by engagement with rolling-stock wheels prior to the arrival of such wheels at the zones of intersection.

8. The combination, with two pairs of intersecting rails capable of traverse by flanged rolling-stock wheels; of movable means positioned within the dimensions of the rails for providing approximately continuous traction surface at the points of intersection of the rails, and means capable of accommodation within the space confined

by the intersecting rails whereby said first named means are operatively inter-related.

9. The combination, with two pairs of intersecting rails capable of traverse by flanged rolling-stock wheels; of movable means positioned within the dimensions of the rails for providing approximately continuous traction surface at the points of intersection of the rails, and means capable of accommodation within the space confined by the intersecting rails whereby said first

named means are operatively inter-related; together with means accommodated within the confines of the rails for moving said first named means.

In testimony whereof, I have signed my name to this specification in the presence of two subscribing witnesses.

MILES F. MOORE.
